(57) **CLAIM**

The ornamental design for a rodent guard for utility poles, as shown and described.

DESCRIPTION

FIG. 1 is an upper, front, left side perspective view of a rodent guard for utility poles, showing my new design; FIG. 2 is a perspective view thereof, showing the guard mounted on a utility pole with lines protruding therefrom; the environment comprising a utility pole and lines are shown in dashed lines for illustrative purposes only.

FIG. 3 is another perspective view thereof, showing the guard mounted on a utility pole with a larger bundle of lines protruding therefrom; the environment comprising a utility pole and lines are shown in dashed lines for illustrative purposes only

FIG. 4 is a front elevational view thereof;

FIG. 5 is a rear elevational view thereof;

FIG. 6 is a left side elevational view thereof, the right side elevation being a mirror image thereof;

FIG. 7 is a top plan view thereof; and,

FIG. 8 is a bottom plan view thereof.

The broken line showing of environment in the drawings is for illustrative purposes only and forms no part of the claimed design.
